BATH SUPPORT FOR BABIES

Kenneth A. Holland, Sr., Kansas City, Mo.

Application May 19, 1947, Serial No. 749,056

6 Claims. (Cl. 4—185)

1

My invention relates to infant's bath appliances, and more particularly to a baby bath appliance that is adapted to be mounted on an ordinary bath tub.

It is a purpose of my invention to provide a baby bath appliance of the above-mentioned character that can be utilized for not only bathing the baby in the ordinary way, but also to give the baby a shower bath if this is desired. In order to make this possible the support for the infant is made of fabric that is pervious so that water will readily pass therethrough and will not collect thereon.

More particularly my invention comprises a bath appliance of the above-mentioned character comprising a fabric member that is mounted on a frame, which is adapted to be supported in a safe manner on any of the usual forms of bath tubs provided in homes. While a bath tub with a roll rim is illustrated in the drawings, other types of tubs can be utilized for supporting my improved bath appliance in a manner that the same will remain safely in position on the tub in the manner in which it is to be used, without any danger of the same slipping off the tub.

It is a specific purpose of my invention to provide a bath appliance of the above-mentioned character that comprises a rectangular frame that is adjustable so as to fit on tubs of various widths and which is provided with stop means thereon that are adjustable relative to the frame so that the frame can be mounted on the rim portion on opposite sides of a tub, whether it is of a roll rim type or of the so-called built-in type of which there is a very narrow ledge on one side of the tub and said stop members will firmly hold the frame in position on the opposed edges or rims of the tub without any danger of the same slipping off said rims or edges.

It is a further purpose of my invention to provide a bath appliance of the above-mentioned character in which the supporting means for the infant comprises a fabric member that is made of one piece of fabric, preferably, rectangular, which is adapted to be detachably mounted on the frame so that the fabric can be removed from the frame readily to wash the same, if this is desired, or for drying purposes if it is preferred to remove the fabric from the frame for this purpose, although the fabric can be dried on the frame also.

Other objects and advantages of my invention will appear as the description of the drawings proceeds. I desire to have it understood, however, that I do not intend to limit myself to the particular details shown or described, except as defined in the claims.

In the drawings:

Fig. 1 is a plan view of my improved bath ap-

pliance showing the same mounted on a bath tub which is partly broken away.

Fig. 2 is a fragmentary sectional view through a bath tub showing my improved bath appliance applied thereto.

Fig. 3 is an enlarged fragmentary sectional view through the adjustable connection between the two portions of the frame whereby the length thereof transversely of the bath tub can be adjusted.

Fig. 4 is an enlarged sectional view through the frame and one of the adjustable stop members, and

Fig. 5 is a fragmentary enlarged sectional view taken substantially on the line 5—5 of Fig. 1.

Referring in detail to the drawings, my improved bath appliance is shown as being mounted on a bath tub 6, which has the rim portions 7, which are shown as being of the roll rim type, although the particular type of tub on which the appliance is mounted is immaterial.

My improved bath appliance comprises a rectangular frame having a pair of side members 8 and 8' that are mounted on the rim portions 7 of the tub when the appliance is in use. Said members 8 and 8' are provided with bends 9 therein, which are made of relatively short radius for a purpose to be described below. The bends 9 connect the side members 8 and 8' with the transverse members 10 and 10'.

The members 8 and 8' are made of tubing and the member 8' is of slightly larger diameter than the member 8 so that the portions 10' thereof telescopically receive the portions 10 of the members 8, the portion 10 telescoping within the portion 10' sufficiently to obtain any desired adjustment in length of the frame to fit tubs of any standard width and still leave a sufficient portion of the member 10 telescoped with the member 10' for rigidity. The members 10' are provided with threads 11 and sleeves 12 are internally threaded to engage with the threads 11. Said sleeves 12 have an inturned flange 13 thereon at the opposite end thereof to the threads thereon, that is provided with an internally beveled face with which the beveled end 14 of a split sleeve 15 engages.

When the sleeve 12 is unscrewed from the threaded portion 11 the split sleeve 15 will be released from the member 10 sufficiently that the members 10 can be slid relative to the members 10' to obtain the desired adjustment of the members 8 and 8'. After such adjustment has been made the sleeves 12 are screwed down tightly on the threaded portions 11, which will cause the split sleeves 15 to be drawn tightly around the member 10 and the engagement of the beveled portion of the inturned end 13 of the sleeve against the beveled shoulder 14 will cause the beveled end 16 of the sleeve 15 to enter the small

space between the members 10' and 10, firmly clamping the parts together in adjusted position.

Mounted on the members 10 and 10' are stop members that have a split tubular portion 17 extending around said members 10 from which a pair of legs 18 extend. Said legs 18 are secured together by means of a headed fastening element 19 and a nut 20 to firmly clamp the portion 17 around the tubular member 10 or 10', as the case may be. When the screw-threaded means is released the tubular portion 17 can be slid along on the member 10 or 10' into such a position as may be desired. Surrounding the parallel legs 18 of the stop member is a sleeve 21 of rubber or similar cushioning material. The stop members are adjusted so that the cushioning members 21 on the members 18 will engage the inner face of the tub 6 adjacent the rims 7, thus preventing any transverse movement of the frame relative to the tub and assuring that the side portions 8 and 8' of the frame will be in engagement with the two rims 7 of the tub. It will be noted that due to the sharpness of the bends 9 the members 17 can be brought much closer to the members 8' and 8 than is shown in the drawings, which makes it possible to adjust the stop members to such a position that the frame can be safely placed on tubs with one or both rims much narrower than that shown in the drawings.

Mounted on the rectangular frame is a rectangular fabric member 22, which is made of a pervious fabric and which is attached to the frame in such a way as to support the infant on the same, this being accomplished by placing the rectangular fabric member cornerwise on the frame so that the corner portions 23 and 24 thereof extend around the tubular frame members to the under side thereof. Tapes 25 and 26 extend from corner to corner on the rectangular piece of fabric entirely across the same in a manner which will be clear from Figs. 1 and 5, the ends of the tapes being tied together as indicated at 27. The tapes are drawn together tight enough in connection with the tying of the same that the fabric member 22 will be drawn taut across the frame in both directions, thus providing a supporting surface for an infant that will have substantially no sag therein, or at least so little sag that the surface thereof will be substantially flush with the top edges of the rim portions 7 of the tub.

Thus the supporting surface for the infant will be neither located below the top surface of the tub so that water can collect thereon due to water that is allowed to stand in the tub, nor will it be located at a point spaced so far above the rim of the tub as to be in danger of tilting or otherwise getting out of fixed position relative to the tub.

What I claim is:

1. A bath appliance of the character described comprising a rectangular frame, means for adjusting the length of said frame, means for holding said frame in adjusted position, stop members projecting downwardly from said frame, a rectangular body supporting member of pervious fabric mounted cornerwise on said frame, and means for detachably and adjustably connecting a pair of opposed corner portions of said fabric body supporting member.

2. A bath appliance of the character described comprising a rectangular frame, means for adjusting the length of said frame comprising telescopically related tubular members, clamping means for holding said tubular members in ad-

justed position, adjustable stop members projecting downwardly from said frame, and a body supporting member of pervious fabric detachably and adjustably mounted on said frame.

3. A bath appliance of the character described comprising a rectangular frame, means for adjusting the length of said frame, means for holding said frame in adjusted position, stop fingers having elongated body portions and clamping portions at one end of said body portions embracing said frame, sleeves of cushioning material embracing said body portions, means for releasably engaging said clamping portions with said frame to permit adjustment of said stop fingers along said frame, and a body supporting member of pervious fabric detachably and adjustably mounted on said frame.

4. A bath appliance of the character described comprising a rectangular frame, means for adjusting the length of said frame, means for holding said frame in adjusted position, adjustable stop fingers projecting downwardly from said frame, cushioning sleeves on said stop fingers, and a body supporting member of pervious fabric detachably mounted on said frame.

5. A bath appliance comprising a rectangular frame comprising a pair of tub engaging side members and telescoping members connecting the same to extend across said tub, tub engaging stop fingers depending from said frame, a pervious fabric body supporting member detachably mounted on said frame, and means for holding said telescoping members in adjusted telescopic relation comprising a split sleeve embracing one of said telescoped members, a sleeve embracing said split sleeve and screw-threadedly engaging the other telescoped member, and cooperating means on said sleeves for wedging said split sleeve into clamping engagement with both of said telescoped members.

6. The combination with a bath tub of a tubular rectangular frame having a pair of sides engaging the top edges of opposed sides of said tub, and a pair of sides adjustable in length extending perpendicularly to said first mentioned sides transversely across said tub in the same plane as said first mentioned sides comprising telescopically related tubular members, a fabric sheet mounted detachably on said frame to extend between said sides in a plane substantially co-incident with the top edges of said tub, and stop members on said frame depending therefrom to engage the inner face of said tub adjacent said side edges, said fabric sheet having portions embracing the adjustable sides of said frame and having corner portions detachably and adjustably connected together to embrace said other pair of sides for any adjustment of said adjustable sides.
